UNITED STATES PATENT OFFICE.

REGINA KAHN, OF MILWAUKEE, WISCONSIN.

GAS-IGNITER.

1,066,623.

Specification of Letters Patent.

Patented July 8, 1913.

Application filed October 7, 1912. Serial No. 724,248.

To all whom it may concern:

Be it known that I, REGINA KAHN, a citizen of the United States, residing at Milwaukee, county of Milwaukee, and State of 5 Wisconsin, have invented new and useful Improvements in Gas-Igniters, of which the following is a specification.

My invention relates to improvements in that class of gas igniters, which are adapted 10 to be centrally located between a plurality of gas burners and by which the gas when turned on to any one or more of said burners, may be instantly ignited by jets of burning gas from said central igniter.

15 Heretofore gas has been led to a pilot light located in a central chamber through a separate small capillary tube while a larger volume of gas has been led to and discharged into said central chamber 20 through a larger tube, whereby when desirous to ignite the gas in any one or more of said burners, the valve leading to said central chamber is opened and quickly closed, whereby a radial jet of flame is 25 caused to flash out from said central chamber to the several burners of the stove, and whereby the gas in any one or more of said burners has been instantly ignited. By 30 my present improvement, however, a separate capillary tube for conducting gas to the pilot light in said central chamber is dispensed with and the required volume of gas for maintaining one or more pilot lights in such chamber is led thereto through the 35 main large duct and the small capillary tube heretofore used for maintaining a pilot light in an igniter is dispensed with.

40 My invention is further explained by reference to the accompanying drawings, in which—

Figure 1 represents a plan view showing a plurality of gas burners and igniter connected with the top of an ordinary stove. Fig. 2 is a side view, part in section, of the 45 igniter removed from the stove, and Fig. 3 is a section of the combustion chamber of the igniter taken on lines 3—3 of Fig. 2.

Like parts are identified by the same reference numerals throughout the several 50 views.

1 represents the top of a stove of ordinary construction and 2 are gas burners used in connection with such stove. The several burners 2 are connected with the main gas supply pipe 3 by the several gas ducts 4, and admission of gas to said gas ducts and

burners is controlled by the several valves 5, all of which parts thus far described are substantially of ordinary construction.

6 represents the central chamber of the 60 igniter. Gas is led from the main gas supply duct 3 to the chamber 6 through the duct 7.

8 is a spherical valve for controlling the 65 passage of gas from the main supply duct 3 to the duct 7. The valve 8 is normally retained in its seat 9 by the recoil of the spiral spring 10, which spring 10 is interposed between the valve 8 and the reducing coupling 11. The valve 8, spiral spring 10 70 and reducing coupling 11 are all located within the valve chamber 12. The valve 8 is adapted to be opened by pressure upon the push button 13 and the push button 13 is connected with said valve by the push rod 75 14, operating through the stuffing nut 15.

It will be understood that a large volume 80 of gas is admitted to the central chamber 6 from the main gas duct 3 by opening the valve 8 and that a pilot light or constant flame is adapted to be maintained in said central chamber 6, whereby when the valve 8 is opened, the gas which is admitted to said chamber is instantaneously ignited when it flashes outwardly radially, as indicated in Figs. 1 and 3, whereby the gas which has been turned on to any one of the several burners 2 is instantaneously ignited as previously stated. The pilot light in the 85 chamber 6 is constantly maintained in the 90 chamber 6 by admitting gas from the main supply duct 3 through a by pass 16, when it passes from thence to said central chamber 6 through the valve chamber 12 and gas duct 7, when four small radial pilot lights 95 are maintained in said chamber 6. When, however, a larger volume of gas is admitted to the chamber 6 by opening the valve 8, such larger volume of gas is instantaneously 100 ignited and caused to flash outwardly radially as heretofore described for the purpose of lighting the gas in any one or more of the several burners. The passage of gas through the by pass 16 is controlled by the needle valve 17 and said valve 17 is adjusted forwardly or backwardly by the threaded member 18 formed integrally therewith, and said member 18 is provided with a knurled head 19 by which it is turned forwardly and 105 backwardly when adjusting the needle valve 17 toward or from its seat. 20 represents the radial ports through which the gas escapes

for maintaining both the pilot lights and producing the radial jets of flame by which gas is ignited in the several burners. The ports 20 are formed in the vertical duct 21, from which the central chamber 6 is supported. The central chamber may be formed of two separate concavo-convex disks as shown in Fig. 2, or it may be formed integrally as desired.

10 Having thus described my invention, what I claim as new, and desire to secure by Letters Patent, is—

15 1. The combination with a main gas supply duct and a plurality of stove burners, of an igniter comprising a central chamber, a branch duct leading from said main gas supply duct to and extending within said central chamber, said branch duct within said central chamber provided with a plurality of radial ports, means for supplying a small amount of gas to said branch duct continuously from said main duct for supplying pilot lights at said radial ports, and an additional means for supplying a larger 25 amount of gas to said branch duct intermittently from said main duct for projecting the pilot lights from the central chamber to the stove burners for igniting the gas in one or more of said stove burners.

30 2. The combination with a main gas supply duct and a plurality of stove burners, of an igniter comprising a central chamber, a branch duct leading from said main gas supply duct to and extending within said central chamber, said branch duct within said central chamber provided with a plurality of radial ports, a by-pass leading from said main supply duct to the radial ports in said central chamber, said by-pass 35 being adapted to permit a small supply of gas to continually pass to said radial ports, whereby a continuous pilot light is maintained at each of said radial ports, and an additional means for supplying a larger 40 amount of gas to said branch duct intermittently from said main duct for projecting the pilot lights from the central chamber to the stove burners for igniting the gas in one or more of said stove burners.

45 3. The combination with a main gas sup-

ply duct and a plurality of stove burners, of an igniter comprising a central chamber, a branch duct leading from said main gas supply duct to and extending within said central chamber, said branch duct within 55 said central chamber provided with a plurality of radial ports, a by-pass leading from said main supply duct to the radial ports in said central chamber, a needle valve for closing the passage of gas through said by-pass, said by-pass being adapted to permit a small supply of gas to continually pass to said radial ports, whereby a continuous 60 pilot light is maintained at each of said radial ports, and an additional means for supplying a larger amount of gas to said branch duct intermittently from said main duct for projecting the pilot lights from the central chamber to the stove burners for igniting the 65 gas in one or more of said stove burners. 70

4. The combination with a main gas supply duct and a plurality of stove burners, of an igniter comprising a central chamber, a branch duct leading from said main gas supply duct to and extending within said 75 central chamber, said branch duct within said central chamber provided with a plurality of radial ports, a by-pass leading from said main supply duct to the radial ports in said central chamber, a needle valve 80 for closing the passage of gas through said by-pass, said by-pass being adapted to permit a small supply of gas to continually pass to said radial ports, whereby a continuous pilot light is maintained at each of said radial ports, additional means for supplying a larger amount of gas to said branch duct intermittently from said main duct for projecting the pilot lights from the central chamber to the stove burners for igniting 85 the gas in one or more of said stove burners, and a valve for manually controlling the admission of such larger supply of gas to said 90 branch duct. 95

In testimony whereof I affix my signature in the presence of two witnesses.

REGINA KAHN.
